COWBOY BOOT

Harry Vise, Nashville, and Robert F. Steakley, Lebanon, Tenn., assignors to Texas Boot Manufacturing Company, Inc., Lebanon, Tenn., a corporation of Tennessee

Filed Sept. 1, 1966, Ser. No. 3,676

Term of patent 14 years

(Cl. D2—273)

FIG. 1

FIG. 3

FIG. 2

FIG. 4

FIG. 1 is a side elevation of a cowboy boot showing my new design.

FIG. 2 is a front elevation.

FIG. 3 is an enlarged fragmentary side elevation showing the ornamental stitching and lined for the colors red, yellow and green.

FIG. 4 is a fragmentary developed plan view showing the specific stitched design on the front of the boot, the stitched design also being adapted to the back of the boot.

The characteristic feature of my design resides in the specific stitched design as best seen in FIG. 4 on a boot as shown.

We claim:

The ornamental design for a cowboy boot, as shown and described.
